UNITED STATES PATENT OFFICE

GEORGE F. WIKLE, OF MILWAUKEE, WISCONSIN, ASSIGNOR TO THE FISK RUBBER COMPANY, OF CHICOPEE FALLS, MASSACHUSETTS, A CORPORATION OF MASSACHUSETTS

BEAD-WRAPPING MACHINE

Application filed July 3, 1925. Serial No. 41,294.

My invention relates to a device for wrapping longitudinally wrapping lengths of material, such as bead cores, used in building pneumatic tire casings, with fabric or other material and more particularly to a device which will apply the wrapping a number of times about a length of material.

In the accompanying drawings which illustrate one embodiment of my invention 10 Figure 1 is a side elevation of the device, the wrapper being omitted in the interest of clearness,

Figure 2 is a plan view of the structure shown in Figure 1,

Figures 3, 4 and 5 are diagrammatic sections showing the wrapping steps, substantially at the lines 3—3, 4—4 and 5—5 of Figure 2.

Figure 6 is a detail of the mounting of 20 the wrapping rolls.

Referring to the drawings 1 designates the supporting standard of a table 2 upon which are mounted the various wrapping instrumentalities. As shown in Figure 1 the bead core 5, drawn from any suitable source of supply, is applied to the fabric strip 6 as the latter passes over a roll 7 from tension rolls 8 and 9, a grooved guide roll 10 pressing the core into adhering contact with the 30 fabric strip. The assembled core and fabric then pass to a preliminary wrapping means comprising a grooved wheel 12 and folding blades 14 and 16. As shown in Figures 3 and 2, the core is applied off center of the strip and blade 16 applies the short edge of the fabric to the core, while blade 14 underlies the longer edge of the fabric and assures the application of the strip to the side of the core in position to be engaged by the 40 first of the series of wrapping rollers 18.

A second guide roller 19 maintains the core in contact with a substantial arc of the wheel 12. The wrapping rollers 18, which are preferably grooved are mounted in opposed pairs 45 as is shown in Figure 2 and are supported by frames 20 secured to table 2 at 21.

The rolls 18 are carried in forked members 22 adjustably mounted in frames 20 by set screws 23. One roll of each pair is spring 50 mounted to apply spring pressed toward the

bead as the latter passes between the rolls. Any suitable form of spring mounting which permits longitudinal and angular adjustment may be used, the form shown, (see Fig. 6) comprising a spring 25 encircling shaft 26 55 of the fork 22, the latter being splined at 27 in a bearing 28 adjustably secured in frame 20 by set screw 23, a pin 29 limiting the outward movement of shaft 26. The opposed rolls 18 are set at reversed angles as 60 is clearly shown in Figures 4 and 5. This angular relation of the rolls imparts a turning or twisting motion to the core as the latter passes through the rolls, thus rolling the core into the wrapper. Figure 4 shows 65 the wrapping about half completed while Figure 5 shows the wrapping nearly completely applied. From the last pair of rolls 18 the wrapped core passes over wheel 30 and around a tension wheel 31 mounted at 70 one end of a lever 32 pivoted to a bracket 33 secured to table 2. A weight 34 attached to the other end of lever 32 urges wheel 31 against wheel 30. The shaft 35 of wheel 30 is connected for rotation to any suitable 75 source of power, not shown, and wheel 12 is driven from shaft 35 by means of a sprocket chain 36 passing around sprockets 37 and 38 mounted respectively on shaft 35 and shaft 39 of wheel 12. 80

The operation may be summarized as follows: The core and fabric strips are brought together as they enter between rolls 7 and 10, the core positioned adjacent one edge of the strip. From rolls 7 and 10 the assembly 85 passes to a preliminary wrapping means comprising a grooved wheel 12 and co-operating folding blades 14 and 16 which bring the wrapper into smooth contact with a major portion of the circumference of the core as shown in Fig. 3, a guide roll 19 maintaining the assembly in contact with a substantial arc of the roll 12. The assembly then passes to the first of the inclined wrapping rolls 18 which roll the core into the fabric, 90 as indicated in Fig. 4, succeeding rolls 18 continuing the rolling action until the core has been completely rolled longitudinally 95 into the strip 6. The core in its completely wrapped condition passes around wheel 30 100

and tension wheel 31. Rolls 12 and 30 being positively driven advance the assembly through the machine, wheel 31 through weight 34 applying sufficient tension to maintain this driving relation. The assembly having been initially threaded or led through the machine the operation proceeds as a continuous operation, the machine being stopped to permit splicing of new lengths to the ends of core 5 and wrapper 6 before the ends of the exhausted supply enter rolls 7 and 10.

While I have shown my invention applied to the wrapping of bead cores it will be understood that my invention is not limited to such use and the word core is used in the claims in a generic sense.

I claim:

1. A device of the character described comprising means for associating a wrapper strip and a core, means for imparting longitudinal motion to the associated strip and core and means to roll the core into the strip.
2. A device of the character described comprising means for associating a wrapper strip and a core, means for moving the associated strip and core longitudinally and means for simultaneously rotating the core to roll the latter into the strip.
3. A device of the character described comprising means for associating a wrapper strip and a core, means for moving the associated strip and core longitudinally, and relatively stationary means in the path of such movement, operative to roll the core into the strip.
4. A device of the character described comprising means for associating a wrapper strip and a core; means for moving the associated strip and core longitudinally and a plurality of rolls arranged to impart rotation to the core about its longitudinal axis to thereby roll the latter into the free portion of the wrapper.
5. A device of the character described comprising means for associating a wrapper strip and a core, means for moving the associated strip and core longitudinally and a plurality of freely rotatable rolls acting on opposite sides of the assembly to impart rotation to the core to thereby roll the latter into the free portion of the wrapper.
6. A device of the character described comprising means for assembling a wrapper strip and a core, means for moving the assembly longitudinally, and a series of rolls positioned on opposite sides of the path of movement of the assembly and arranged to impart motion thereto to roll the core progressively into the free portion of the wrapper.
7. A device of the character described comprising means for assembling a wrapper strip and a core, means for moving the assembly longitudinally, and a series of rolls

arranged in pairs to engage substantially opposite sides of the assembly to thereby impart rotation thereto about its longitudinal axis to roll the core progressively into the free portion of the wrapper.

8. A device of the character described comprising means for assembling a wrapper strip and a core, means for moving the assembly longitudinally and a series of grooved rolls arranged in pairs to engage substantially opposite sides of the assembly the rolls of each pair being rotatable in planes inclined to each other.

9. A core wrapping element comprising a pair of grooved rolls engaging opposite sides of the core said rolls being rotatable in planes inclined to each other.

10. A core wrapping element comprising a pair of grooved rolls engaging opposite sides of the core, said rolls being freely rotatable in planes inclined to each other.

In testimony whereof I have signed my name to the above specification.

GEORGE F. WIKLE.
